UNITED STATES PATENT OFFICE.

EDWIN L. PALMBORG, OF FOREST HILLS, MASSACHUSETTS.

JOINT-GRINDER.

1,209,996.

Specification of Letters Patent. Patented Dec. 26, 1916.

Application filed June 1, 1915. Serial No. 31,329.

To all whom it may concern:

Be it known that I, EDWIN L. PALMBORG, a citizen of the United States, residing at Forest Hills, county of Suffolk, State of Massachusetts, have invented an Improvement in Joint-Grinders, of which the following description, in connection with the accompanying drawing, is a specification, like characters on the drawing representing like parts.

This invention relates to an improvement in grinding machines.

This apparatus is adapted to grind steam pipe joints of the class known as ball joints. 15 In steam pipes, due to contraction and expansion attendant upon highly variant temperatures, it is essential to have well fitting connections in the pipes carrying the live steam. Such necessity is particularly notable 20 in the joints in what is known as the niggerhead of locomotives.

A pipe, known as the dry pipe, is placed inside the boiler and runs longitudinally thereof, carrying the live steam destined for 25 consumption in the cylinders. This dry pipe projects into the smoke-box at the front of the locomotive. The niggerhead is the T-shaped head which is on the smoke-box end of the dry pipe and functions to provide a 30 two-way connection therewith for the steam pipes leading to the cylinders. In addition to the obvious desirability of preventing the depreciation of the steam pressure at the niggerhead, it is essential that this joint 35 should not leak as the escape of steam at this point would lessen, if not totally destroy, the partial vacuum which is maintained for purposes of draft in the smoke-box. As these joints become corroded and

40 roughened in use, with the resultant escape of steam, it is necessary to grind the concave faces of these ball joints to insure a steam-tight connection. For this purpose the usual door of the locomotive front plate is opened 45 which furnishes access to the niggerhead. The present practice is to disconnect the steam pipes from the niggerhead and to grind these joint surfaces by hand within the small and restricted space available with- 50 in the smoke-box of the locomotive. Such procedure entails great loss of time and the expenditure of labor unnecessary when using this new and improved device.

The apparatus, the subject of this invention, is adapted to be inserted in the smoke-

box of a locomotive upon the opening of the usual door of the front plate. Its supporting arm is bolted to the flange surrounding the joint to be ground. This arm has a ball and socket engagement with the grinding device proper so that it may be moved when in operation relatively to the arm, resulting in a symmetrically ground joint surface. The grinding device consists of a ring composed of an abrasive material and has one 60 convex face and a flat face so that it is adjustably adapted to grind either a concave or a flat surface. A handle is secured to the grinder frame for its facile manipulation while the geared grinding portion is driven 65 by means of a telescoping shaft from a suitable power source. Upon the proper grinding of one joint face the grinder arm is removed and bolted to the flange of the other joint and that surface similarly treated. 70

The object, therefore, of this novel construction is to provide an abrasive means adapted to grind pipe joints when a restricted space is afforded.

Another object is to provide a joint 75 grinder adapted to be movably held against a ball joint and which is provided with an arm by which it may conveniently be manipulated while in operation.

A further object is to provide such a 80 grinder with a flexible and extendible power shaft permitting effective operation of the grinding apparatus in various sized and shaped inclosures and at variant distances from the power source. 85

In order to afford an understanding of this invention, a selected embodiment has been illustrated in the accompanying drawings and will now be described.

Figure 1 is a side elevation view of the 90 grinder, motor and platform as positioned in a locomotive smoke-box; Fig. 2 is a plan view of one end of the adjustable platform; Fig. 3 is a section on the line 3—3, Fig. 2; Fig. 4 is a sectional view of a niggerhead 95 with the grinder in position and shows the positioning means; Fig. 5 is a side view in elevation of the grinder with the universal and telescoping shafting; Fig. 6 is a section on the line 6—6, Fig. 5; Fig. 7 is a longitudinal section through the bracket and showing the slot. 100

The T-shaped coupling or niggerhead 1 has two openings or steam ways, the surfaces 2 of which are arcuate or spherical. 110

These openings have annular flanges 3 having holes 4 therein by which means the steam pipe connections are bolted to the niggerhead. In the views shown, the steam connections have been removed in order to position the grinder.

The grinder proper is adjustably retained in place by means of the angled supporting bracket 5 which is adapted to be secured in 10 threaded engagement in one of the bolt holes 4 of the annular flanges 3. As shown in Fig. 4, the grinder is positioned in the right side opening in the head. The grinder proper consists of a frame having three 15 arms 6, 7 and 8. The frame arm 6 has an enlarged portion 9 which furnishes a bearing for the shaft 10 of the driven bevel gear 11. The gear 11 is adapted to mesh with and actuate the gear 12 whose shaft 13 is 20 journaled in the enlargement 14 at the union of the three frame arms. The shaft 13 has revolvably secured thereto, by the nut 15, a disk or plate 16 interposed between the washers 17 and 18. The plate 16 is adapted 25 to carry thereon the abrasive which is shown as a ring 20 having, in section, substantially the form of a spherical segment. This ring 20 is reversibly mounted so that two effective abrading surfaces are afforded, a convex face 21 and a flat face 24.

The ring 20 is adjustably and reversibly positioned on the plate 16 by means of posts 22 having threaded transverse holes in which are placed, in threaded engagement, 35 the screws 23 whose ends impinge against the inner face 25 of the ring 20. The posts 22 are four in number and are preferably equidistantly disposed in circular alignment on the plate. The posts are carried in the 40 radially disposed slots 26 cut in the plate. The post ends, projecting through the slots, are threaded and have a washer 27 and nut 28 secured on each by which means the posts are radially adjustably secured in the slots. 45 Through the co-operation of the radial slot and screw adjustments, different sized rings may be retentively held in a plurality of positions and by such means wear may be taken up and the rings accurately centered 50 and eccentricity of rotation may be avoided.

The frame end opposite the abrasive has an enlarged portion 29, apertured to receive in slidable engagement the shaft 30 which has a collar 31 pinned thereon to limit its 55 outward movement. The shaft 30 at the other end has a preferably integral and substantially hemispherical head 32. The helical spring 33 is placed about the shaft 30 between the head 32 and the frame portion 29 60 and functions to hold the post normally outwardly extended. The head 32 is adapted to be received in engagement with the socket 34 of the block 35 carried on the end of the threaded stem 36. The tension of the block 65 on the head 32 and hence of the abrasive

ring in the ball joint is adjustably applied by means of the longitudinal movement of the stem with relation to the bracket 5.

The bracket 5, adjacent its end opposite to the joint flange, is slotted longitudinally. 70 A box, which is adapted to be placed in the bracket slot, has a central threaded aperture and a flange 37, on one end. The other end of the box which projects through the bracket slot has an exteriorly threaded portion on which is received in threaded engagement the lock nut 38. The box is thus longitudinally adjustably secured in the slot through the co-operation of the flange 37 and the lock nut 38. The stem 36 is received in 75 threaded engagement with the box aperture and hence may be moved in a plane normal to the bracket surface by turning a hand wheel 39 which is preferably integral with the stem. A lock nut 40 is placed upon the 80 stem to insure retention thereof in a predetermined position of adjustment. The grinder, in this manner, holds in adjustably tensioned contact the abrasive ring 20 and the surface 2 of the joint. The ball and 85 socket union, made by the head 32 and the socket 34 of the block 35, permits the relative movement of the grinder. A handle, as shown in Fig. 6, secured in an arm 8 of the frame affords a facile mode of manipulation 90 of the frame. This handle is preferably composed of a handle portion 52, secured at its upper end in one end of an elbow 41, the other end of the elbow being adapted to be secured to either of the arms 7 and 8 by 95 means of an aperture 42 provided in each. This adjustability of the handle functions to afford means by which the grinder frame may be manipulated from either side as, due to space restriction in a locomotive smoke- 100 box, the frame is not operable from the same side when mounted in the right as when mounted in the left way of the niggerhead.

This grinding apparatus is provided with a telescoping universal-jointed shafting increasing the range of effective operation of 110 this device in restricted closures. The main driven shaft 43, actuated by any suitable power means, terminates in a universal joint 44, to which is secured the spindle 45. The 115 latter has cut longitudinally therein a keyway 46, shown in dotted lines in Fig. 2. The spindle 45 is inserted in a tube 47. An aperture is milled in the tube and a key 48 is 120 inserted therein and has sliding engagement with the keyway 46, making the tube 47 revolvable with, and longitudinally slidable with relation to, the spindle 45. This tube is positioned within the sleeve 49 and revolvably secured thereto. A key 50 is inserted 125 in an aperture through the sleeve and tube and engages the keyway 46 of the spindle 45—equalizing the torsional strain on the spindle. The continuation of the sleeve forms part of the universal joint 51 through 130

the medium of which the shaft 10 carrying the bevel gear 11 is actuated. While this apparatus may be actuated by any convenient form of power, it is preferably driven by means of an electric motor 72, adjustably positioned upon a platform detachably mounted within the smoke-box shell 54. This platform consists of two angle irons 55 which have their ends united by means of blocks 56 welded thereto. The end portions of the platform are similar. Each block 56 has a threaded aperture in which is received in engagement the threaded stem 57 fixedly secured at its outer end to the head 58 to which are bolted the slotted bars 59. The platform angle irons 55 are similarly slotted and, by means of the bolts passing through the opposed slots are retained by the nuts 60. The slidably adjustable bars 59 may be guided or locked in position. The pointed supports 61, affixed to the head 58, provide contacts to impinge against the inside of the smoke-box shell and their tension thereagainst is regulated by the turning of the threaded stem 57 in the end block 56 which functions to extend the head and forcibly to press the supports against the shell. The rotation of the stem is effected by means of the insertion of a rod, pin or similar object within the apertures 62 of the enlarged stem portion 63. A three point suspension is provided for the platform by means of the pivoted support 64 normally received within one of the heads 58. This pivoted support 64 is formed on the reduced end portion of the stem. When a three point suspension is desired the head at this end is removed so that this support only is outwardly presented to a smoke-box shell. Provision for such suspension is made as it has greater adaptability to smoke-box shells of smaller radii. The motor is, as shown in Fig. 1, provided with means for its adjustable emplacement on the platform 53. The motor casing has an axial extension 65 in which is formed a threaded aperture receiving in retentive engagement the threaded reduced portion 66 of the stud 67. The stud is adapted to pass through a longitudinal platform opening afforded by the angle irons 55. A flange 68 is carried by the stud at its upper end and provides a relatively wide base to rest upon the surfaces of the platform. The lower stud end has a threaded reduced portion 69 projecting below the platform and receiving thereon the handle 70, the head 71 of which is interiorly threaded to engage the stud end. The motor-supporting stud is thus slidably mounted upon the platform and may be locked, upon the rotation of the handle, at any desired point thereon.

In operation the apparatus is simple and efficiently rapid. The door of the locomotive front plate is opened, the two steam pipes are disconnected, and the motor plat-

form is installed. If a flat surfaced joint is to be ground, the plane face 24 of the abrasive ring is outwardly presented, while, if the usual concave surfaced joint is to be ground, the convex face 21 is presented. The abrasive ring is trued on the plate 16 by means of the adjustable screw posts. If it is desired to grind the right side ball joint first, the handle with its elbow is positioned in the aperture 42 in the left member 8 of the frame. The bracket 5 is bolted to the flange surrounding this joint. The grinder frame is then positioned so that the abrasive ring 20 impinges against the surface 2 of the joint while the head 32 engages the socket 34 of the block 35. The tension of the block 35, carried on the end of the threaded stem 36, is regulated by the hand wheel on the other stem end. The box is accurately positioned in the longitudinal slot 75 in the bracket 5 so that the stem 36 will be in alinement with the shaft 30 carrying the ball head 32. The box is retentively held in such position by tightening lock nut 38. The hand wheel 39 is then rotated, the stem 36 turns in the box and thus the socket block is pressed against the yieldable head 32, forcing it toward the frame against the tension of the spring 33. The motor is then attached to the universal shaft, placed on the stud support, and the support positioned and locked on the platform. Power is thus applied to the driven shaft, and, through the bevel gears 11 and 12, the plate 16 and ring 20 are rapidly revolved and the surface 2 is ground. The grinding operation is manually directed and controlled through the handle secured to the frame by means of which the frame and hence the grinding ring is moved with relation to its yieldable spring 105 ball and socket support. In practice, a sheet iron jacket is bolted to the frame arms and functions to inclose the bevel gears and thus to protect the hands or fingers of an operative therefrom. After one ball joint has 110 been correctly ground, the bracket 5 is removed and bolted to the flange surrounding the other joint, the handle is secured to the arm 7 of the frame, the motor slidably positioned and locked, and a similar process is 115 repeated.

There is thus provided a labor-saving, efficiently simple and expeditiously operated grinder capable of effective operation in the limited space afforded in a smoke-box.

Having fully described my invention, what I claim as new and desire to secure by Letters Patent is:

1. In a grinding machine, a rotatable grinding element, means for positioning said element against the surface to be ground, means for changing the contacting portions of the element and the surface while said surface is being ground.
2. In a grinding machine, a rotatable

- grinding element, a support for said element adapted yieldably to position the same against the surface to be ground, a handle on said support whereby said element and support may be moved to vary the contacting portions of the element and of said surface while said element is operatively held against said surface. 5
3. In a grinding machine, a frame, a grinding element adjustably mounted on said frame, a handle on said frame, a support for said frame, means carried by said support yieldably and movably to retain the grinding element against the surface to be ground whereby the contacting portions of the element and the surface may be varied while the surface is being ground. 10
4. In a grinding machine, a rotatable grinding element, a holder for said element adapted yieldably to position the element against the surface to be ground, a plurality of engaging means on said holder adapted selectively and interchangeably to receive a handle whereby said holder support may be manipulated when said element is operatively held against said surface. 15
5. A grinding machine comprising a frame, a grinding member mounted upon a shaft in said frame, a bearing member on said frame in axial alinement with the shaft and having a spherical bearing head, supporting means adapted to be secured to the object to be ground, a socket on said means adapted to engage said spherical bearing head, and means on the frame to change the contacting portions of the grinding member and the object ground while in operation. 20
6. A grinding machine comprising a frame, a grinding element borne by the frame, a support for the frame to hold the grinding frame in tensioned contact with the object to be ground, means on said support and said frame to permit relative movement therebetween when in operative position, a flexible driving means to actuate the grinding element, and a handle on the frame operable to change the contacting portions of the grinding element and the object ground during the grinding operation. 25
- 50 7. A grinding machine comprising a frame, a support therefor, a spherical headed bearing member on said frame, a socket on said support to receive the spherical head of said member, a grinder, a shaft for the grinder in axial alinement with the bearing member, a beveled gear upon the grinder shaft, a coöperating bevel gear mounted upon a shaft at right angles thereto and a driving member operatively secured by a universal joint whereby the last-mentioned shaft is actuated and said grinder may be moved while functioning. 55
8. A grinding machine of the character described including a grinding ring, a driving shaft, a revoluble plate, a plurality of posts radially disposed on the plate, a set screw transversely received in adjustably threaded engagement in each of said posts and adapted to impinge against the inner face of, and adjustably to position, said ring 60 on said plate. 65
9. In a grinder for ball joints, a revoluble grinding element, a bracket adapted to be secured to a ball joint flange and having a transverse slot therein, a screw box adjustably secured in said slot, a threaded stem adapted to be adjustably positioned in said box in axial alinement with said revoluble element, a bearing member on said stem adapted adjustably to position the element 70 on the surface to be ground. 75
10. A grinding machine comprising a frame, a handle on said frame, a revoluble grinding element mounted on said frame, yieldable frame-supporting means comprising a shaft mounted in said frame in axial alinement with the revoluble element, a bearing head on said shaft and a resilient means on said shaft intermediate said head and said frame, and a support to engage 80 said head whereby said frame may be manipulated by said handle while said grinding element is operatively held against the surface to be ground. 85
11. A grinder for grinding a pipe joint 95 retained within an inclosure, a grinding element, a revoluble support therefor, means affixed to said joint for holding said support, a shaft adapted to rotate said revoluble support, power means to actuate said shaft, 100 an extendible platform adapted to be positioned within said inclosure and means for locking said power means in a plurality of positions on said platform. 105
- In testimony whereof, I have signed my name to this specification.

EDWIN L. PALMBORG.
